UNITED STATES PATENT OFFICE.

FRITZ BECKER, OF LONG ISLAND CITY, NEW YORK, ASSIGNOR TO NATIONAL
LABELING MACHINE COMPANY.

LABELING MACHINE.

Application filed May 17, 1922. Serial No. 561,589.

To all whom it may concern:

Be it known that I, FRITZ BECKER, a citizen of the United States, and resident of Long Island City, in the county of Queens and State of New York, have invented certain new and useful Improvements in Labeling Machines, of which the following is a specification.

This invention relates to labeling machines, and is particularly intended for use in affixing labels to articles so formed as to readily stand on end, for example, tin cans of the type commonly used in the distribution of food materials.

An object of the invention is to provide a machine by which labels may be smoothly and permanently affixed to the ends of articles, which may be readily adapted for operation on articles of widely varying heights or lengths, and which may also be used to affix labels to articles of very small transverse dimensions, as well as to those of larger transverse dimensions.

To this end an important feature of the invention resides in the combination with means for locating a label to an article to be labeled of label affixing members movable to and fro into and out of abutting relation with the article to affix the label thereto. In the present embodiment of the invention, the label affixing devices are fulcrumed on the machine frame on opposite sides of the support for the article, and in accordance with a further feature of the invention such devices include blocks to the under surfaces of which are secured label engaging members, the blocks being offset away from each other at their lower portions and the label engaging members being secured to the blocks by clamping means of less thickness than the degree of offset of the lower portions of the blocks, so as to enable the blocks and, consequently, the label engaging members to be brought close together in the operation of the machine, thus adapting the machine for use in affixing labels to articles of very small transverse dimensions.

Other objects and features of the invention will appear as the description proceeds and will be pointed out in the appended claims.

In the drawings in which like reference numerals designate like parts in the various views:

Fig. 1 is a view in side elevation of a labeling machine constructed in accordance with the invention; 55

Fig. 2 is also a side elevation, parts being broken away better to reveal the operating connections for the label affixing devices; 60

Fig. 3 is a front view looking from the right in Fig. 2;

Fig. 4 is a detail view partly in section of one of the label affixing devices; and

Fig. 5 is a view in plan of the article support.

The illustrated machine comprises a frame 2 on the front side of which is mounted a bracket 4, and secured to the upper end of the bracket 4 is a support 6 for the article to be labeled. As shown, the machine is designed particularly for affixing labels to the ends of cylindrical articles, such as the one indicated at A in Figs. 1 and 3. Accordingly, the support 6 is constructed to support an article on end, and in order to position the article support 6 is preferably formed on its upper face with an upstanding rib 8 which, as most clearly shown in Fig. 5, is generally crescent-shaped and is arranged to engage the periphery of the article adjacent to its lower edge. The article A is, preferably, also positioned on the support 6 and maintained in upright position by means of an upright 10 formed to present a curved forward surface arranged for engagement with the periphery of the article adjacent to its upper surface.

Mounted stationarily at the top of the frame 2 is a label container 12, and a carrier 14 comprising spaced arms transfers the labels singly and successively from the bottom of the container 12 to a point adjacent to the top of the article A. The labels are then engaged by a presser foot 16 provided in its under surface with an insert 18 of soft and yielding material, such as rubber or the like, the presser foot 16 and insert 18 being arranged between the spaced arms of the transference 14 in the central, vertical plane of the article A when in position on the article support 6, and operating to engage the central portion of the label and press it against the top of the article substantially in the central plane of the article. During each cycle of operations of the machine, a suitable adhesive is applied to the label engaging surfaces 20 at the ends

of the transferrer arms 14, the adhesive material being contained in a pot 22 stationarily supported on the frame 2. The transferrer 14, presser foot 16 and the means for applying adhesive to the surfaces 20 of the transferrer arms 14 from the pot 22 may be, and preferably are, constructed and arranged as described in my copending application for Letters Patent of the United States, Serial No. 561,588 filed May 17, 1922. The transferrer arms, presser foot and adhesive applying means are operated from the main cam shaft 24 of the machine by means designated generally in Fig. 1 by the numerals 26, 28 and 30 respectively and are also constructed and arranged as fully described in said application. Accordingly, a more complete description in this application of such features of the illustrated machine is deemed unnecessary.

The labels are affixed permanently in place on the article A by means including arms 32 fixed to shafts 34 journalled for angular movement in bearings 36 secured to the frame 2 at the front side of the machine. The arms 32 (Fig. 3) are deflected laterally and inwardly at points indicated by 38 substantially at right angles, and adjustably connected to the free ends of the arms by bolt and slot connections 40-42 are metal strips 44, the free ends of which are bowed downwardly. The bowed strips 44 support blocks 46 formed at their upper ends with bifurcations 48 which receive between them the downwardly bowed ends of the strips 44. Preferably, and as shown, the blocks 46 are offset at their lower portions away from the central vertical plane of the article, as indicated at 50, for a purpose which will more clearly appear hereinafter. Disposed below the bottom surfaces of the blocks 46 and in engagement therewith are label engaging members 52 of suitable material, such, for example, as rubber or rubber composition, the members 52 being of somewhat greater dimensions than the offset lower portions of the blocks 46 and being secured to the blocks 46 by clamps 54 surrounding the blocks and the upper portions of the members 52. The clamps 54 may be secured to the blocks 46 by set screws 55, and each of the clamps acts to compress the members 52 within dimensions corresponding to those of the lower portions of the blocks, so as to cause the members 52 to be firmly fixed to the blocks by frictional engagement with the inner surfaces of the clamps 54. The thickness of the clamps 54, preferably, does not exceed the extent of offset of the blocks 46 at 50, so that no portion of the clamps extends beyond the inner and adjacent faces 56 of the blocks when they are in label affixing position, as shown in broken lines in Fig. 3.

Fixed to the shafts 34 at their rear ends are short arms 57 pivoted to the upper ends of operating rods 58, the lower ends of which pass loosely through eyes formed in yokes 60. At their lower ends the rods 58 are provided with nuts 62 between which and the yokes 60 are interposed springs 64 acting to maintain the yokes 60 normally against collars 66 fast on the rods 58. The yokes 60 in turn are joined at their lower ends to arms 68 fast on a shaft 70 extending transversely on the machine frame 2 and being provided at the left-hand side of the machine (Fig. 3) with a third arm 74. The arm 74 is formed in its upper end with a slot 76 for adjustable connection to a rod 78 joined at 80 to the upper end of a lever 82 fulcrumed at 84 on the machine frame 2 and being provided with a roller 86 arranged for riding engagement upon the periphery of a cam 88 on the main cam shaft 24. The roller 86 is maintained against the cam 88 by a spring 90 connected at one end to the lever 82 and at its other end to a suitable fixed point 92 (Fig. 1) on the machine frame. From the foregoing, it will be understood that the adjustable connection provided by the rod 78 and arm 74 enables the downward movement of the label affixing blocks 46 to be adjusted so as to adapt the machine for operation on articles of varying widths, and that the yielding connection between the yokes 60 and the operating rods 58 further enables the machine to adapt itself readily to operation under varying conditions by permitting the blocks 46 to yield upwardly when necessary with relation to their operating means.

The general principles of the operation of the present machine are similar to those of the machine described in my above-mentioned application, and may be briefly summarized as follows:

The transferrer arms 14 are moved upwardly to cause their label engaging surfaces 20 to be pressed against the under surface of the bottom label in the container 12. The surfaces 20 have previously had a suitable adhesive applied thereto, thus causing the label engaged by them to adhere to them and to be moved downwardly with them to a point adjacent to the upper surface of the article A on the support 6. The presser foot 16 is moved downwardly concurrently with the transferrer arms 14, and the felt insert 18 of the presser foot engages the label at its central part between the arms 14 and presses such portion of the label against the article while the label is disengaged from the transferrer arms 14 by subsequent upward movement of the arms. The label affixing blocks 46 are then operated downwardly to cause the label engaging members 52 to press the ends of the label tightly into engagement with

the article to be labeled, as indicated in Fig. 3. By reference to Fig. 3, it will be seen that the blocks 46 and label engaging members 52 in their label affixing positions are disposed very close to the presser foot 16, such arrangement of the parts being permitted by the offsetting of the lower ends of the blocks 46, and the fact that the thickness of the clamps 54 is such as not to exceed the degree of offsetting of the blocks 46 at 50, so that the clamps 54 do not extend beyond the adjacent surfaces 56 of the upper portion of the blocks 46.

By the use of the present invention labels 15 may be affixed very smoothly and securely to the ends of articles, for example, tin cans such as are commonly used in the distribution of food materials. Moreover, inasmuch as the presser foot 16 and felt insert 20 18 are relatively thin, as seen in Fig. 3, and the label affixing members 52 are caused to engage the labels very close to the presser foot, the machine is adapted to affix labels to articles ranging upwardly in size from 25 a very small diameter. It will be manifest from the foregoing, that the invention is applicable to operation on articles of widely varying sizes and under a wide range of conditions.

30 Although the invention has been described in its application to affixing labels to the ends of cylindrical articles, it is recognized that it is applicable also to affixing labels to the ends of articles generally, which can be made to stand on end, and that certain 35 features of the invention may be utilized in affixing labels to portions of articles other than their ends. Accordingly, it is intended that the scope of the invention shall not be 40 limited except as required by the claims.

Having fully described the invention, what is claimed is:

1. In a labeling machine, an article support, rock shafts arranged at each side of 45 said support, an angular arm fixed to each of the rock shafts, a locally yieldable label clamping member secured to one end of each of said arms, and cam actuated mechanism 50 operatively connected to the rock shafts and including an adjustable connection for regulating the extent of rocking movement of said shafts.

2. In a labeling machine, an article support, a rock shaft arranged at one side of 55 said support, an angular arm fixed to one end of said shaft, a locally yieldable label clamping member secured on the free end of said arm, and actuating mechanism operatively connected to the other end of said 60 rock shaft and including an adjustable con-

nnection whereby the extent of rocking movement of the shaft may be regulated.

3. In a labeling machine, a frame, an article support carried by the frame and constructed to support an article on end, a label 65 container, and means for applying a label to the upper end of the article comprising a carrier for transferring labels successively from the label container to a point adjacent to the article support, means for maintaining the label in engagement with the upper end of the article in the central vertical plane of the article, label affixing members fulcrumed on said frame on opposite sides 70 of the support, and adjustable means for 75 yieldably pressing the label affixing members against a label on opposite sides of the presser foot to affix the label to the article.

4. In a labeling machine, an article support, and means for applying a label to an 80 article on the support comprising a presser foot for maintaining the label against the article, and label affixing members comprising pivoted arms, blocks mounted on the 85 ends of said arms and offset at their lower portions in directions away from the central, vertical plane of an article on the support, a label engaging member of yieldable material carried by each of the blocks in engagement with its bottom surface, said label 90 engaging members being of somewhat greater dimensions than said blocks, and clamping means for securing said members frictionally to the offset lower portions of the blocks. 95

5. In a labeling machine, means for applying a label to an article, comprising pivoted arms, blocks secured at their upper ends to said arms and having their lower ends offset away from each other, a yieldable 100 label engaging member carried by each of said blocks in engagement with its bottom surface and of somewhat greater dimensions than the block, and clamps surrounding the offset lower ends of the blocks for securing the label engaging members thereto, said clamps being of such thickness with relation 105 to the extent of the offset of the lower portions of the blocks from the upper portions as not to project beyond the adjacent faces 110 of the upper portions of the blocks when the blocks are in label affixing position, thereby enabling the label engaging members to engage a label at points closely adjacent to each other. 115

In testimony that I claim the foregoing as my invention, I have signed my name hereunder.

FRITZ BECKER.
